UNITED STATES PATENT OFFICE.

LUTHER V. MOULTON, OF GRAND RAPIDS, MICHIGAN.

DESIGN FOR A FRAME FOR MARINE VELOCIPEDES.

SPECIFICATION forming part of Design No. 27,153, dated June 1, 1897.

Application filed May 3, 1897. Serial No. 634,955. Term of patent 14 years.

To all whom it may concern:

Be it known that I, LUTHER V. MOULTON, a citizen of the United States, residing at Grand Rapids, in the county of Kent and State of Michigan, have invented and produced a certain new and original Design for Frames and Wheel-Houses for Tandem Marine Velocipedes; and I do hereby declare the following to be a full, clear, and exact description of the invention, reference being had to the accompanying drawings, forming part thereof.

This design relates to the frame and wheel-house for tandem marine velocipedes and analogous structures, and the distinctive features thereof are the oppositely-curved sills and segmentally-curved bars of the wheel-house and the upper and lower curved bars of the frame, as more fully illustrated in the accompanying drawings, in which—

20 Figure 1 is a perspective of a frame and wheel-house embodying said design, and Fig. 2 a side elevation of the same.

Like letters refer to like parts in both of the figures.

25 A represents the sill of the wheel-house, having a general inclination of about forty-five degrees, being nearly horizontal at its extreme ends and oppositely curved longitudinally, the lower part being convex on the under side and concave on the upper side and the upper part having an opposite curvature.

B is a bar having a substantially semicircular longitudinal curvature and joined at each end to the respective ends of the sill A.

D is a semicircular plate near the middle 35 of the sill A, and C C C are a series of radial bars extending from said plate to the bar B.

E is a slightly downwardly-curved bar prolonging the line of the sill A and having an upward curve E', concave at the forward side 40 and terminating at the upper end in a reverse curve E".

F and F are curved bars arranged in series and alike in form and located above the bar E and in the same vertical plane, each bar F 45 having an inwardly-curved forward end F' and an upward and forwardly curved rear end F" and extending in connected series from the rear of the upturned forward end of the bar E to the forward side of the bar B. 50 Hangers G, having curved diverging arms, connect the nearest adjacent parts of the bars E and F.

It is obvious that said design may be readily adapted to land velocipedes as well. 55

Having thus fully described my invention, what I claim is—

The design for a frame and wheel-house for a tandem marine velocipede, substantially as shown and described. 60

In testimony whereof I affix my signature in presence of two witnesses.

LUTHER V. MOULTON.
